UNITED STATES PATENT OFFICE.

DAG AGNAR ENGSTRÖM, OF STOCKHOLM, SWEDEN.

CARD REGISTER.

Application filed July 29, 1925, Serial No. 46,733, and in Sweden August 23, 1924.

This invention has reference to a card register in which the cards are not placed in boxes or cases, but are joined together into a band, strip or chain, to be rolled upon and off of rollers, and are to be deposited rolled up. When a card is to be read, or anything annotated on it, the roller which contains the card in question, is placed on a shaft, which together with still another roller and shaft, is adapted to be journaled in a box or frame, whereby the card chain can be rolled onto, or off of said rollers in such way that any card in the chain can be brought into visible position.

15 The shafts may either be turned by hand, or by means of a small electric motor. In the former case, it is advantageous to use a gearing between the crank and the shafts, whereby the shafts are given sufficient speed. 20 The card register as per this invention offers many advantages in comparison to such registers as keep the cards in boxes or cases. Separate cards cannot be removed from the collection, or be exchanged, as easily and unnoticeably as in other systems. The rolled-up chain can be sealed, and all undue manipulation is thus excluded, unless the seal be broken. The card register consequently offers the very best security against illegitimate or criminal manipulations, which makes it especially usable in bookkeeping.

Another advantage is that this card register can be stored on shelves, or wherever space permits. Hereby the generally used and specially designed boxes will be unnecessary, which involves a great saving. Furthermore the cards, when rolled up, require but little space and the register may therefore advantageously be used in cases where the registered material must be kept for future use, as in offices, archives, banks, etc.

In the drawings, Fig. 1 is a side view showing two cards embodying the invention and connected together;

25 Fig. 2 is a perspective view on a smaller scale showing a complete card register embodying the invention enclosed in a box or housing.

The device comprises a box or casing 10 having an opening 14 in its upper face. The card register is in the form of a plurality of cards 15 which are joined together in the

form of a chain, these connected cards being rolled onto rolls carried by two shafts 6 and 7 which are journaled in the box 10. The 55 shafts have cranks 8 and 9 extending therefrom by which they may be turned and the box is provided in its side with slots 11, 12 in which the shafts operate, the purpose of these being to permit the ready removal of 60 the shafts from the box. Situated in the box beneath the side opening 14 is a rest or bridge 13 over which the chain of connected cards passes as the cards are rolled from one shaft onto the other.

65 The cards are connected together in a special way so as to permit their being readily separated one from another if it is desired at any time to place additional cards in the register. For this purpose each card is 70 formed on one edge with a series of hook members 1, each having a T-shape as best seen in Fig. 1, and on the opposite edge each card is formed with a series of openings 2. Each of the openings 2 has a wide portion 75 of a width to receive the wide end of the T-shaped projection and a narrow neck portion of a width to receive the neck of the projection. The projections 1 are integral with the card and lie in the plane thereof. 80 When a card is to be taken from or put into the chain of connected cards all that is to be done is to place the card or the space desired for the card directly on the bridge 13 and then unhook the chain of cards at this point. In thus disconnecting any two cards 85 it is not necessary to bend the hooks or projections as they can be readily hooked into or unhooked from the openings without bending. Moreover, during the use of the cards 90 these hooks are not bent and since this is so there is little likelihood that they will become broken.

Having now described my invention, what I claim as new and desire to secure by Letters Patent is:

95 1. In a card register comprising a box or casing and rolls journaled in said casing, a plurality of connected cards adapted to be wound on said rolls, each card having near 100 one edge a plurality of openings and at the opposite edge having integral therewith a plurality of hooked members lying in the plane of the card, said openings having a

shape corresponding to that of the hooked members, whereby said hooked members on one card may be interlocked with or separated from the openings in the adjacent card without being bent.

2. In a card register comprising a box or casing having a sight opening and rolls journalled in the casing, a plurality of connected cards wound on said rolls, each card

having a plurality of T-slots in a row near one edge and also having integral therewith at the other edge a plurality of T-shaped projections which lie in the plane of the card and which are adapted to be detachably interlocked with said openings. 10 15

In witness whereof, I have hereunto signed my name.

D. AG. ENGSTRÖM.
